BARREL-CHANGING DEVICE FOR AUTO-
MATIC FIREARMSEmil Murbach, Budapest, Hungary, assignor of
one-half to "Danuvia" Ipari és Kereskedelmi
R. T., Budapest, Hungary, a firmApplication November 30, 1936, Serial No. 113,349
In Germany December 2, 1935

4 Claims. (CL. 42—75)

My invention enables me to provide for the change of the hot barrel of automatic firearms by one movement of the hand of the operator and without the help of moving parts of the 5 fore-arm of the weapon.

The invention is shown in Figs. 1, 2, 3 and 4.

Fig. 1 is a longitudinal section of the firearm, showing the barrel in its firing position.

Fig. 2 shows how the barrel is lifted from the 10 firearm.

Fig. 3 shows the flash shield, arranged for modification of the recoil.

Fig. 4 shows the handle of the barrel at a somewhat enlarged scale.

15 Referring to the drawing, 1 denotes the receiving or stock portion of the fire-arm from the forward end of which a supporting or semi-cylindrical guide 2 projects, the open side of the latter being arranged along the top. The outer

20 or muzzle end of the guide 2 is cylindrical and internally threaded to receive the threaded shank of an outwardly flared flash concealing shield 3. The flash concealing shield 3 is tapered outwardly in its inner wall in opposite directions, 25 25 the diameter of the opening being smallest just short of its inner end.

Supported in the flash-concealing shield 3 is the muzzle end of a barrel 4, which fits closely in the smallest diameter of the flash-concealing 30 shield 3, and which because of the oppositely tapered bore thereof is capable of being tilted upwardly out of axial alignment with the flash-concealing shield 3 to permit removal, as illustratively exemplified in Figure 2.

35 The opposite or breach end of the barrel 4 is removably secured in the stock 1 by any suitable means, but for illustrative purposes, an arrangement has been adapted which comprises a series of interrupted transverse ribs and a

40 sleeve 5 embracing the barrel inside the ribs and being adapted to abut the end of the stock when the barrel is in firing position. The sleeve 5 carries a radial arm having an axially projecting handle. The inner end of the barrel 4 is locked

45 in firing position by means of a lever catch 8 pivotally mounted on the radial arm and disposed with its opposite ends overlying the sleeve 5 and handle, respectively. A spring 9 is mounted in the handle and engages the under side of the

50 lever 8 to urge it upwardly, whereby the opposite end thereof which is provided with a tooth 10 is engaged in an opening running through the sleeve 5 and barrel 4 to prevent rotation of the latter.

Adjacent the outer or muzzle end of the barrel

4 is a fixed collar 6 which acts as a stop, abutting the inner end of the flash-concealing shield 3, when the barrel is released and projected in order to raise the breach end, as shown in Figure 2. 5

To change the barrel one hand of the operator grasps the handle 5, one finger pressing down the right arm of the catch 8, thus lifting its tooth 10 from the corresponding cut in the sleeve 5. The barrel may then be turned and pushed 10 forward about 1 to 1.5 inches, until its collar 6 abuts the flash-concealing shield 3. The barrel is then retracted from its seat and can be tilted upwards and lifted from the barrel guide 2.

The fresh barrel is brought into position by 15 manipulating in the reverse order. The muzzle of the barrel will easily glide into the flash-concealing shield.

In some cases the flash-concealing shield preferably can be adapted for modifying the recoil. 20 This is done by designing its fore part so as to form a central circular diaphragm 7, the opening of which may be of a smaller diameter than that of the outside of the muzzle of the barrel. This diaphragm 7 is placed sufficiently far in 25 advance of the muzzle to permit forward movement of the barrel in order to release it from the receiver or stock 1. The diaphragm 7 is preferably integral with the walls of the flash shield although it may be a separate piece mounted in 30 and attached to the latter.

The invention can be made use of with automatic arms either with moving or with stationary barrel.

Having now particularly described and ascertained the nature of my said invention, and in what manner the same is to be performed, I declare that what I claim is:

1. In a firearm of the character described, the combination with a stock and extension therefor 40 of a removable barrel, supported in the stock and extension and a flash-concealing shield rigidly secured to the outer end of the extension and having a bore tapering inwardly from opposite ends to form a throat adjacent the rear end of 45 the shield for supporting the muzzle end of the barrel, while the double taper permits the same to be tilted and withdrawn from the shield, the barrel being of such length that, when its rear end is locked to the stock, its muzzle end is 50 spaced well back from the front end of the shield to permit hot products of combustion discharged from the muzzle to expand and be retained temporarily in the enlarged bore of the outer end of the shield. 55

2. A firearm, as claimed in claim 1, in which the taper at the inner end of the shield has a greater angle than the taper at the other end.

3. A firearm, as claimed in claim 1, having a collar fixed on the barrel short of the muzzle end thereof to abut the supporting piece and limit the forward movement of the barrel when being removed and replaced in the firearm.

4. A firearm, as claimed in claim 1, compris-

ing a handle carried on the rear end of the barrel, and a spring controlled latch pivoted to said handle and provided with a tooth to engage simultaneously notches in the barrel and extension to prevent the barrel in its firing position from rotating out of connection with the extension.
